Patented Oct. 24, 1967

208,970

DOOR KNOCKER

Theodore A. Sawallesh, 3011 Westcott St.,
Falls Church, Va. 22042

Filed May 24, 1966, Ser. No. 2,416

Term of patent 14 years

(Cl. D10—7)

FIG. 3.

FIG. 2.

FIG. 1.

FIG. 4.

FIG. 7

FIG. 6.

FIG. 5

FIG. 8.

FIG. 1 is a view in front elevation of a door knocker embodying my new design for a striker unit therefor;

FIGS. 2, 3 and 4 are views respectively in side elevation, top plan and rear elevation of the door knocker of FIG. 1;

FIG. 5 is a view in front elevation of a modified form of door knocker embodying the new design for a striker unit similar to that of FIGS. 1 to 4 inclusive; and

FIGS. 6, 7 and 8 are views respectively in side elevation, top plan and rear elevation of the modified form of door knocker as shown in FIG. 5.

I claim:

The ornamental design for a door knocker, substantially as shown and described.
